[57] CLAIM

The ornamental design for a shoe upper, as shown and described.

DESCRIPTION

FIG. 1 is a left side elevational view of a shoe upper showing my new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a left side elevational view of an alternate embodiment of my new design;

FIG. 7 is a right side elevational view thereof;

FIG. 8 is a top plan view thereof;

FIG. 9 is a front elevational view thereof;

FIG. 10 is a rear elevational view thereof;

FIG. 11 is a left side elevational view of an alternate embodiment of my new design;

FIG. 12 is a right side elevational view thereof;

FIG. 13 is top plan view thereof;

FIG. 14 is a front elevational view thereof; and,

FIG. 15 is a rear elevational view thereof.

The broken line showing of a shoe sole in the figures is environmental only and forms no part of the claimed design.
